P. R. FORTIN

ELECTRON DISCHARGE APPARATUS

Filed Feb. 12, 1921

Inventor:
Paul R. Fortin,
by *Paul R. Fortin*
His Attorney.

UNITED STATES PATENT OFFICE.

PAUL R. FORTIN, OF SCHENECTADY, NEW YORK, ASSIGNOR TO GENERAL ELECTRIC COMPANY, A CORPORATION OF NEW YORK.

ELECTRON-DISCHARGE APPARATUS.

Application filed February 12, 1921. Serial No. 444,524.

To all whom it may concern:

Be it known that I, PAUL R. FORTIN, a citizen of the United States, residing at Schenectady, county of Schenectady, State of New York, have invented certain new and useful Improvements in Electron-Discharge Apparatus, of which the following is a specification.

My present invention relates to electron discharge apparatus, and more particularly to means for cooling one of the electrodes of an electron discharge device.

In one form of electron discharge device which comprises an incandescent cathode, an anode and a grid enclosed in an evacuated receptacle, a portion of the receptacle is made of metal and this metal portion of the receptacle is utilized as the anode. In the operation of such devices, particularly when high potentials are employed, a large amount of heat is produced at the anode and it therefore becomes desirable to provide means for artificially cooling the anode. The object of my invention is to provide a simple and efficient means for accomplishing this result.

The novel features which I believe to be characteristic of my invention are set forth with particularity in the appended claims. The invention itself, however, both as to its organization and method of operation will best be understood by reference to the following description taken in connection with the accompanying drawing in which Fig. 1 shows partly in perspective and partly in section one embodiment of my invention and Fig. 2 is a plan view of a portion thereof.

As indicated in the drawing, the cooling means which I provide for the electron discharge device 1 comprises a container 2 for a cooling liquid which may be employed to cool the anode 3 of the device. The container 2 is provided with a large amount of radiating surface by means of a plurality of tubes 4 extending vertically therethrough. The pipe 5 connects the bottom of the container 2 with the top. The anode 3 of the electron discharge device is inserted in an opening 6 in the pipe 5, and a liquid tight joint is made at this opening so that the liquid circulating in the pipe 5 cannot leak out around the anode 3. In the operation of the cooling means the liquid around anode 3 is heated and rises through the pipe 5 to the top of the container 2. The liquid is

then cooled in container 2 and circulates toward the bottom of the container and back through the pipe 5; thus a continuous natural circulation of the cooling liquid is provided. The cooling of the liquid in the container 2 is facilitated by causing a blast of air to flow through the pipes 4, this blast of air being furnished by the fan 7 which directs the air through a conduit 8 of insulating material into the tubes 4.

In the ordinary operation of the electron discharge device 1, the anode 3 is maintained at a high potential with respect to the other electrodes of the device and with respect to earth, and it is essential that the container 2 be insulated from earth. This is accomplished by mounting the container 2 upon an insulator 9 by means of a pivotal connection 10 so arranged that the container 2 may be rotated about the horizontal axis when it is desired to remove the device 1 from the pipe 5. This is desirable in order that the liquid in the container shall not leak out through the opening 6 when the device 1 is removed.

In order to provide an electrical connection to the anode 3 a contact member 11 is secured to the pipe 5 and when the container is in its normal operating position this contact member 11 makes contact with stationary clips 12. When the container 2 is rotated to remove the device 1, this contact is automatically broken.

A pair of contacts 13, of which only one are shown in the drawing, are mounted upon an insulating base 14 secured to bracket 15 on the top of the container 2. These contacts are connected to the terminals of the cathode of the device 1, and when the container 2 is in its normal operating position make contact with stationary contact members 16 to which the source of current supply for the cathode may be connected. When the container 2 is rotated to remove the device 1, the connections to the cathode are also automatically broken between contacts 13 and 16.

The terminal for the grid electrode 18 is usually brought out on one side of the portion 17 of the evacuated receptacle as indicated in Fig. 2. A stationary contact member 18 may also be provided for making contact to the terminal of the grid electrode.

It will be noted that by the arrangement shown and described, the container 2 is

- 2
- insulated from all parts of the apparatus which are connected to earth by means of the insulator 9 and the insulating conduit 8, and that connections to the electron discharge device must be broken before the device can be removed from the container. Any possibility of accident to the operator in removing the device 1 is therefore eliminated.
10. The ear 19 with a hole therethrough, which is formed on the container 2, permits of the rotation of the container about horizontal axis 10 by means of a hook with an insulated handle thereon.
15. While I have shown and described the preferred embodiment of my invention, it will be apparent to those skilled in the art that my invention is by no means limited to the specific structure shown, and that many 20 modifications therein may be made without departing from the scope of my invention as set forth in the appended claims.
- What I claim as new and desire to secure by Letters Patent of the United States, 25 is,—
1. The combination with an electron discharge device having an exhausted receptacle, a portion of which consists of metal, the metal portion of said receptacle forming 30 one of the electrodes of said device, of a container for a cooling liquid, a pipe connecting the bottom of said container with the top, said pipe having an opening therein in which the metal portion of said receptacle may be inserted so as to be in contact with the cooling liquid flowing in said pipe, said container being insulated from earth and having switching means secured thereto through which current may be supplied 35 to said electron discharge device and being rotatably mounted about an axis.
2. The combination with an electron discharge device having an exhausted receptacle, a portion of which consists of metal, the metal portion of said receptacle forming 40 one of the electrodes of said device, of a container for a cooling liquid, a pipe connecting the bottom of said container with the top, said pipe having an opening therein in which the metal portion of said receptacle may be inserted so as to be in contact with the cooling liquid flowing in said pipe, said container being insulated from earth and having switching means secured thereto through which current may be supplied 45 to said electron discharge device and being rotatably mounted about an axis.
3. The combination with an electron discharge device having an exhausted receptacle, a portion of which consists of metal, the metal portion of said receptacle forming 50 one of the electrodes of said device, of a container for a cooling liquid, a pipe connecting the bottom of said container with the top, said pipe having an opening therein in which the metal portion of said receptacle may be inserted so as to be in contact with the cooling liquid flowing in said pipe, said container being insulated from earth and having switching means secured thereto through which current may be supplied 55 to said electron discharge device and being rotatably mounted about an axis in such a way that when in its normal position the circuit connections to said electron discharge device will be closed by said switching means and when the container is rotated to another position the circuit connections will be opened.
6. The combination with an electron discharge device having an exhausted receptacle, a portion of which consists of metal, the metal portion of said receptacle forming 60 one of the electrodes of said device, of a container for a cooling liquid, the apparatus being so arranged that the cooling liquid surrounds the metal portion of said receptacle and that cool liquid will flow naturally toward the metal portion of said receptacle, said container being insulated from earth and having switching means secured thereto through which current may be supplied 65 to said electron discharge device and being rotatably mounted about an axis, in such a way that when in its normal position the circuit connections to said electron discharge device will be closed by
- 70
- 75
- 80
- 85
- 90
- 95
- 100
- 105
- 110
- 115
- 120
- 125
- 130

said switching means and when the container is rotated to another position the circuit connections will be opened.

7. The combination with an electron discharge device having an exhausted receptacle a portion of which consists of metal, the metal portion of said receptacle forming one of the electrodes of said device, of a container for a cooling liquid for cooling the metal portion of said receptacle and supporting means for said container comprising circuit connections for supplying current to the electrodes of said device, said container being rotatably mounted on the supporting means about an axis in such a way that when in its normal position the circuit connections for supplying current to the electrodes of the device will be closed and when the container is rotated to another position the circuit connections to the device will be opened.
8. The combination in an apparatus of the class described of a container adapted to hold a cooling liquid, means associated with said container for providing a circulation 25 of cooling liquid around an electrode of an electron discharge device and supporting means for said container comprising circuit connections for supplying current to the electrodes of an electron discharge de- 30 vice, said container being adapted to be moved with respect to said supporting means in such a way that in one position of the container the circuit connections for supplying current to the electrodes of an electron dis- 35 charge device will be closed and when the container is moved to another position the circuit connections will be opened.

In witness whereof, I have hereunto set my hand this 11th day of February, 1921.

PAUL R. FORTIN.
